[57] CLAIM

The ornamental design for a case for carrying neckties, as shown and described.

DESCRIPTION

FIG. 1 is a front elevational view of a closed case for carrying neckties showing my new design, the rear elevational view being the same;

FIG. 2 is a right side elevational view, the left side elevational view being the mirror image thereof;

FIG. 3 is a top plan view thereof;

FIG. 4 is a bottom plan view thereof;

FIG. 5 is a reduced front elevational view of the case of FIG. 1 opened;

FIG. 6 is a rear elevational view of FIG. 5;

FIG. 7 is a left side elevational view of FIG. 5;

FIG. 8 is a right side elevational view of FIG. 5;

FIG. 9 is a top plan view of FIG. 5;

FIG. 10 is a bottom plan view of FIG. 5;

FIG. 11 is a front elevational view of a second embodiment similar to FIG. 1, the rear elevational view being the same;

FIG. 12 is a right side elevational view of FIG. 11, the left side elevational view being the mirror image thereof;

FIG. 13 is a top plan view of FIG. 11;

FIG. 14 is a bottom plan view of FIG. 11;

FIG. 15 is a reduced front elevational view of the case of FIG. 11 opened;

FIG. 16 is a rear elevational view of FIG. 15;

FIG. 17 is a left side elevational view of FIG. 15;

FIG. 18 is a right side elevational view of FIG. 15;

FIG. 19 is a top plan view of FIG. 15; and,

FIG. 20 is a bottom plan view of FIG. 15.

The shadow outlines of a necktie in FIGS. 5 and 15 are for illustrative purposes only and form no part of the claimed design.
